UNITED STATES PATENT OFFICE.

KARL JOHAN SVENSSON, OF LIDINGO VILLASTAD, AND KARL AXEL PATRIK NORLING,
OF SODERTORNS VILLASTAD, SWEDEN.

APPARATUS FOR LIFTING OUT AND CLEANING CENTRIFUGAL DRUMS.

Application filed October 4, 1926, Serial No. 139,441, and in Sweden October 13, 1925.

When submitting to centrifugal treatment liquids containing solid particles or impurities which, to a great extent, accumulate in the drum during separation, it is very important to enable such solids to be removed quickly, as the time required for cleaning is an unproductive period of the life of the apparatus. As a rule these solids (due to the high centrifugal force) form a hard and compact layer which must be scraped off or broken loose before it can be removed, and generally, this cannot be done conveniently in vertical centrifugal apparatus with the drum remaining in the machine body; so that the drum has to be lifted out and tilted to a predetermined angle. It is desirable that the drum, or that part thereof which contains the separated solids, should be tilted to such an extent that the solids scraped off from the walls of the drum can be poured out together with any liquid remaining therein.

For large centrifugal drums which are inconvenient to lift out from the body by hand, a mechanical hoisting device of some suitable kind must be used, but it is difficult to make a suitable apparatus for gripping the drum or its heavy parts in such a way that it will be easy to tilt them and secure them at the required angle. Various means have been constructed for this purpose but they all present disadvantages, as for instance, that the drum must first be lifted out and placed in a special apparatus or that the lifting device is secured to the outside of the drum. The former method requires extra space to be available in the neighbourhood of the apparatus and the latter that the machine body must be made so large that the device can pass between the body and the drum.

The present invention has for its object, a device for gripping a vertical centrifugal drum, or the part thereof containing the separated solid impurities, in such a manner that the drum when being lifted out of the machine body has, always, a tendency to remain vertical but at the same time may be tilted over easily to any required angle from 0° up to over 90°.

According to this invention a link which is adapted at its upper end to be secured to a suitable hoisting arrangement, and at its lower end to be secured to the drum or a part thereof, is so arranged that the latter

connection is effected within the drum and so that pivotal movement may take place about a horizontal axis situated in a vertical plane in which lies the centre of gravity of the drum or drum part and at a suitable distance thereabove, the link being cranked towards one side in such a manner that the top edge of the drum or drum part can pass considerably over the line between the ends of the link so that the said drum or drum part always has a tendency to remain in a vertical position when being lifted out, but may be tilted over easily to any required angle.

One form of the invention is illustrated by the accompanying drawings whereof Figure 1 is a side elevation of the device applied to the bottom part of a drum shown in section, Figure 2 is a plan view thereof, and Figure 3 a side elevation showing the device in use, the drum part shown in these figures being of a well known type having a centre part upstanding from the bottom and bored out from beneath to receive the upper part of the spindle (not shown), by which the drum is supported and driven.

As shown the bottom part *a* of a drum has an upstanding centre part *b*. *c* is a clamp adapted to grip the centre part *b*, and may be made either in one resilient piece or, as shown, in two halves, pivoted about a pin *d*. The clamp *c* is carried by two diametrically opposite horizontal pintles *e* *e* fixed thereto so that, in use, their common axis is situated in the vertical plane in which lies the centre of gravity *f* of the drum part *a*; said pintles engaging apertures in the limbs of the bifurcated end of a cranked link *g* the upper end of which is provided with a ring or the like *h* for the attachment of the device to a hoisting arrangement (not shown). The cranking of the link *g* and the pivotal arrangement of the clamp *c* makes it possible to tilt the drum part *a* one side so that its upper edge can, to a considerable extent, pass over the line between the suspension ring *h* and the pintles *e*, *e*, as shown in Figure 3 where the drum part *a* is tilted over as much as the shape of the link *g* permits, which is more than 90°. Consequently, the impurities and any liquid remaining in the drum part *a* can be poured out while said part is suspended by the apparatus.

In order to facilitate the tilting a bar *j*

is inserted in the bore of the upstanding centre part *b*, which bar is provided at its free end with a chain *h* or the like having a number of rings or loops such as *m* fixed thereto at different distances from the end of the bar *j*. By threading one of these rings on the hook *n* of the hoisting arrangement, the drum part *a* can be tilted and secured at any angle suitable for cleaning.

10 By making the clamp *c* so that it surrounds the centre part *b* without undue pressure, the drum part *a* can be swivelled about its axis even in an inclined position, which facilitates the cleaning. As the pintles *e e* are situated above the centre of gravity of the drum part *a* the latter will always be in stable vertical equilibrium when lifted out of the machine and by making the distance between said pintles and centre of gravity 15 short the tilting force required will be slight, especially if a bar *j* be used as shown in Figure 3.

The present invention is not, however, limited to the device shown in the drawings 25 but, obviously, can be varied in detail in accordance with the design of the drum. Instead of the clamp *c* with horizontal pintles *e, e*, the centre part *b* could be formed with a through-hole for a pin or the like passing 30 through the holes in the bifurcated end of the link *g*, or formed with two diametrically opposed holes near its lower end, in which could be inserted, sliding pins or screws fitted to the bifurcated end of the link *g*.

35 Instead of a single link with a bifurcated end, two separate links suitably shaped and secured together may be employed.

For a centrifugal drum without a centre part, such as *b*, rising from the bottom, a couple of uprights can be fixed on to the 40 bottom of the drum, said uprights being formed at their top ends with holes through which one or two pins or pegs, fitted to the link *g*, can be inserted for tilting.

We claim:—

1. A device for lifting out and cleaning a vertical centrifugal drum or that part thereof in which the separated solid impurities accumulate, comprising a single bifurcated link cranked towards one side and 45 adapted at its upper end to be secured to a suitable hoisting arrangement, and means at the lower end of said link adapted to be secured to a part of said drum inside the latter, said means being movable about a 50 horizontal axis which is situated in a vertical plane in which lies the centre of gravity of the drum and which is situated at a suitable distance above said centre of gravity.

2. In combination with a device for lifting out and cleaning a vertical centrifugal drum or drum part, as claimed in claim 1, the drum being formed with a bore to receive a loose driving spindle, a bar adapted 65 to be inserted in said bore and provided with means adapted adjustably to be fixed relatively to the upper suspension point of the device so that the drum can be secured in any desired inclined position during clean- 70 ing.
